UNITED STATES PATENT OFFICE

ANDREW J. DODGE AND JOHN C. PETTIBONE, OF ANSONIA, CONNECTICUT

WINDOW SCREEN

Application filed March 31, 1927. Serial No. 179,748.

This invention relates to window screens, and has for an object to provide an improved mounting for a screen, which when the window is closed will be wound up into a relatively small space where it is out of the way and is protected against deterioration from the action of the elements or from other injury.

It is also an object of the invention to provide a construction of this type in which the act of opening the window will bring the screen into position, and in which there is locking means for simultaneously clamping the window and screen in any desired position.

It is a further object of the invention to provide a construction for this type of screen in which there is an approved and convenient means for quickly attaching or detaching the screen to or from the sash, and in which the mounting for the screen may be easily removed for storing the screen or it may be as easily mounted in position.

With the foregoing and other objects in view, we have devised the construction illustrated in the accompanying drawings forming a part of this specification. In these drawings,

Fig. 1 is a front elevation of a window showing our improved screen in position, the lower sash of the window being raised to open position.

Fig. 2 is a transverse vertical section thereof substantially on line 2—2 of Fig. 1.

Fig. 3 is a horizontal section through the sash above the screen.

Fig. 4 is a vertical section through the upper supporting bar for the screen showing the clamping means in elevation.

Fig. 5 is a vertical section through the clamp operating means substantially on line 6—6 of Fig. 4, and

Fig. 6 is a front elevation of the socket and the sash used to secure the top bar of the screen thereto.

The upper and lower sashes of the window are indicated at 10 and 11 respectively, and they are mounted to slide vertically in a frame 12 in the usual manner. The glass carried by the sash is indicated at 13. Our im-

proved screen 14 is composed of the usual wire mesh which should, however, be preferably of relatively soft copper wire so as to be fairly flexible. It is connected at its lower end to a spring operated roller 15 and at its upper end is detachably connected to the lower bar 16 of the lower sash. It may, of course, be used on the upper sash in the same manner if desired. The wire mesh 14 is attached at its upper end to a horizontal bar 17, and means are provided for detachably connecting this bar to the lower bar 16 of the sash. For this purpose on the front of the bar 16 are mounted a pair of plates 18 having an elongated opening 19, the sash bar being recessed behind this opening. Mounted in the upper bar 17 of the screen is a pair of T-head bolts 20, these bolts extending through the bar 17 and mounted for turning movements therein. The T-heads 21 are on the rear of the bar and are adapted to pass through the elongated openings 19, and then if the bolt is turned ninety degrees the head will be transverse to this slot and will securely fasten the bar 17 to the bar 16 of the sash. The bolt is easily manipulated by a small handle 22 at the front of the bar 17, and a knurled check nut 23 may be threaded on this bolt at the front of the bar, and when the bolt is turned to bring the head across the opening 19 this nut may be tightened to clamp the bolt in this position. Of course, when the T-head is brought to the upright position the bar 17 may be easily removed from the sash, thus detaching the screen from the sash.

On the inner surface of the upright sides of the frame are mounted upright guides 24 for the upright edges of the screen and also the locking or clamping means. These guides are preferably of sheet metal and are preferably of substantially the shape shown in Fig. 3, there being an open slot 25 in their inner walls for the screen and the clamping members. These guides hold the edges of the screen straight and prevent passage of insects past these edges, and also provide means to cooperate with the locking device.

The locking device is mounted in the horizontal bar 17. This bar is provided with a longitudinal groove 26 in the top wall in

which are seated the clamping members 27, these members having sliding fit in this groove. These clamps are preferably flat strips of metal arranged on edge in this groove, and at their outer ends extend through the slots in the guides 24 and are preferably bent laterally, as shown at 28, to give a better contact and also to prevent withdrawal from the guides during normal operation. These clamping elements have inclined ends at the center of the bar engaging the opposite side edges of a cam plate 29. This plate has inclined upright side edges 30 which engage the inner ends of the clamps 27 and 15 at its lower edge is bent laterally to form a flange 31. Mounted above this flange is an eccentric 32 engaging the top of this flange and mounted on a transverse shaft operated by a crank 33. A spring 34 is connected at 20 its opposite ends to the clamps 27 on opposite sides of the cam plate 29. This spring tends to draw the clamps against the plate. It will be obvious that after the window and the screen has been adjusted to the proper position the operator may turn the crank 33 to operate the eccentric and force the cam plate downwardly. This will force the clamping elements 27 outwardly and clamp their ends 25 against the bottom surfaces of the guides 30 24, and will thus lock the screen and the window in any given position desired. By turning the crank in the opposite direction it will be obvious that the window and screen may be unlocked. This is a very desirable 35 feature because the lock can be operated only from the inside of the window, and therefore, the window may be locked from the inside in any position desired.

As indicated above, the lower end of the screen 14 is connected to a spring operated roller 15. This roller is mounted in a sheet metal casing 35 so that it is enclosed, and when the screen is lowered it is protected by this casing. The roller 15 is operated by a 40 coil spring not shown, which tends to rotate it in a direction to wind up the screen, this being clockwise, as viewed in Fig. 2, so that when the sash is lowered the screen is automatically wound by this spring. The spring 45 is connected to a crank 40 having a handle 41 forming a key by which the spring may be wound to the proper tension. After being wound this crank is inserted into an open sided groove 42 in a metal mounting plate 43, 50 this groove being conveniently formed by pressing the center of the plate laterally. The plate is mounted in the side of the window frame and is secured therein by any suitable means. The front end of this 55 groove opens through the front so that the key may be inserted from the front. The mounting 43 carries a spring finger 45 adapted to retain the crank in the mounting. The finger also rests over the handle 41 to 60 assist in preventing turning of this handle.

This end of the roller is mounted on a plug 48 rotatable on the bar 39. At the opposite end of the roller is a pivot pin 53 adapted to project into a bearing opening in the plate mounting 54. This mounting is mounted in 70 the side of the window frame and secured by any suitable means. The roller may be easily removed for storage or for any other purpose desired, and it may be as easily remounted in the window when desired. Of course, as the 75 window sash is raised a corresponding amount of the screen is unwound from the roller, and when the sash is lowered the screw is automatically wound by the spring operated roller.

It will be apparent from the foregoing description that the construction is very simple, that the screen is on the inside of the window where it is protected from the elements, and is in extended position only 80 when the window is opened and then only to the extent to which the window is opened so that there is always a clear view through the window. It may be easily removed by merely detaching the T-bolts 20 and removing the 85 roller from its mounting at the lower part of the frame. It is as easily remounted by merely inserting the roller and the T-bolts. By means of the clamping elements 27 and their operating crank 33 the screen and 90 window are easily locked in any position to which the window may be moved.

Having thus set forth the nature of our invention, what we claim is:

1. In combination, a movable window sash, a bar to which a screen is attached at one end, guides for the opposite side edges of the screen, means for rigidly securing the bar to the sash so that the bar is required to move therewith in both directions, movable clamping elements carried by the bar and extending at their outer ends into said guides, and manually operable means carried by the bar to shift said elements to press their outer ends against the bottoms of the guides to lock both the window and screen in adjusted positions.

2. In combination, a movable window sash, a bar to which a screen is attached at one end, means for rigidly securing the bar to the sash so that the bar is required to move therewith in both directions, said bar having a longitudinally extending groove, clamping elements mounted to slide in said groove, a cam mounted on the bar and adapted to shift 110 said elements outwardly to press their outer ends against the window frame to clamp both the window and screen in adjusted positions, and manual means for operating the same.

3. In combination, a movable window sash, a bar to which a screen is attached at one end, means to rigidly secure the bar to the sash to move therewith in both directions, said bar having a longitudinally extending 120

groove, clamping elements mounted to slide in said groove, a cam comprising a plate having inclined side edges and a laterally extending lug, said cam being arranged between said elements, a spring tending to hold said elements against said inclined edges, an eccentric mounted to engage said lug, and means to turn said eccentric to separate the clamping elements.

5 10 In testimony whereof we affix our signatures.

ANDREW J. DODGE.
JOHN C. PETTIBONE.
